UNITED STATES PATENT OFFICE.

WILLIAM F. WAGNER, OF NORTH BRADDOCK, PENNSYLVANIA.

BOLT-KEEPER.

1,353,440.

Specification of Letters Patent. Patented Sept. 21, 1920.

Application filed April 24, 1919. Serial No. 292,255.

To all whom it may concern:

Be it known that I, WILLIAM F. WAGNER, a citizen of the United States, residing at North Braddock, in the county of Allegheny and State of Pennsylvania, have invented a new and useful Bolt-Keeper, of which the following is a specification.

The device forming the subject matter of this application is a keeper, adapted to be used in connection with a bolt on a door, and one object of the invention is to provide a keeper which may be mounted in place without cutting away the jamb of the door or disfiguring the outer edge of the door jamb as is done when an eye of the common sort is mounted on the jamb to receive the end of the bolt.

Another object of the invention is to provide a keeper of the sort above mentioned which, at the will of an operator may be inserted at one end between the stop strip and a jamb and be disposed in a horizontal position, or be mounted in a vertical position on the stop strip or some other part of the frame in which the door operates.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in front elevation, a portion of a door and door jamb whereunto the device forming the subject matter of this application has been applied; Fig. 2 is a horizontal section taken through the bolt and the keeper as disclosed in Fig. 1; Fig. 3 is a sectional detail showing the keeper used in a way which differs from the application delineated in Figs. 1 and 2; and Fig. 4 is a perspective disclosing the keeper.

Referring to Figs. 1, 2 and 3, the numeral 1 denotes a frame carrying a jamb 2 on which a stop strip 3 is mounted. A hinged door 4 is adapted to abut against the stop strip 3 and fits within the jamb 2. A bolt

casing 5 is mounted on the door 4, a bolt 6 operating in the casing.

In carrying out the invention, there is provided a keeper 7, in the form of a relatively thin, elongated plate, preferably made of metal, the plate being pointed at one end, as indicated at 8. The plate or keeper 7 is supplied with any desired number of apertures 9, located as convenient, and adapted to receive screws 10 or other securing devices. That end of the plate or keeper 7 which is remote from the point 8 is provided with an opening 11. Intermediate its ends, the plate or keeper 7 is supplied with an opening 21, located nearer to one longitudinal edge of the plate than is the opening 11.

In practical operation, the pointed end 8 of the keeper 7 is driven between the jamb 2 and the stop strip 3, thus holding the keeper in place temporarily. The screws 10 are then mounted in some of the apertures 9 and enter the jamb 2 to hold the keeper 7 in place permanently. The end of the keeper 7 which is provided with the opening 9 projects beyond the jamb 2, as clearly disclosed in Fig. 2, the bolt 6 being received in the opening 11. The keeper 7 is thin enough so that it can be inserted into the space between the edge of the door 4 and the adjacent surface of the jamb 2. It is to be observed that the construction is such that the outer surface of the jamb 2 is not marred or disfigured in any way, as occurs if a common keeper or eye is attached to the exposed outer face of the jamb. The pointed end 8 of the keeper 7, obviously, facilitates the driving of one end of the keeper into place between the strip 3 and the jamb 2.

In Fig. 3, the numeral 12 marks the frame, the door appearing at 14 and the stop strip 15. The bolt casing is shown at 16 and carries the bolt 17. The keeper 7 is mounted in a vertical position on the stop strip 15 and is held in place by screws 18, one end of the bolt 17 being received in the opening 21.

The construction of the keeper 7 is such that it may be used either as disclosed in Fig. 2 or as disclosed in Fig. 3, depending upon whether the bolt is on the outside of the door or upon the inside of the door.

The keeper may be fashioned at trifling expense out of stock which would otherwise be wasted and in mounting the keeper in place, it is unnecessary to cut away the door frame or mutilate the same otherwise.

110

Having thus described the invention, what is claimed is:—

A bolt-keeper in the form of a thin, elongated, flat plate pointed at one end, the plate being provided adjacent to its other end with a first bolt-receiving opening, the plate being provided intermediate its ends with a second bolt-receiving opening, the second opening being located closer to one longitudinal edge of the plate than is the first

opening, the plate having an aperture for the reception of fastening means.

In testimony that I claim the foregoing as my own, I have hereto affixed my signature in the presence of two witnesses.

WILLIAM F. WAGNER.
